(57) **CLAIM**

The ornamental design for a LED lamp, as shown and described.

DESCRIPTION

FIG. 1 is a perspective view of a LED lamp showing a first embodiment of our new design.

FIG. 2 is another perspective view of the first embodiment;

FIG. 3 is a front view of the first embodiment;

FIG. 4 is a rear view of the first embodiment;

FIG. 5 is a left side view of the first embodiment;

FIG. 6 is a right side view of the first embodiment;

FIG. 7 is a top view of the first embodiment;

FIG. 8 is a bottom view of the first embodiment;

FIG. 9 is a perspective view of a LED lamp showing a second embodiment of our new design;

FIG. 10 is another perspective view of the second embodiment;

FIG. 11 is a front view of the second embodiment;

FIG. 12 is a rear view of the second embodiment;

FIG. 13 is a left side view of the second embodiment;

FIG. 14 is a right side view of the second embodiment;

FIG. 15 is a top view of the second embodiment; and,

FIG. 16 is a bottom view of the second embodiment.

The portion of the LED lamp shown in gray shading shown in FIGS. 9-16 is representative of a semi-transparent or transparent appearance.

The broken lines in the drawings illustrate portions of the LED lamp which form no part of the claimed design.
